CLAIM

The ornamental design for packaging container with surface ornamentation, as shown and described.

DESCRIPTION

FIG. 1 is a perspective view of a first embodiment of packaging container with surface ornamentation embodying our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top view of the packaging container with surface ornamentation in an unfolded state;

FIG. 9 is a perspective view of a second embodiment of packaging container with surface ornamentation embodying our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a top view of the packaging container with surface ornamentation in an unfolded state.

The broken lines in the drawing represent environmental subject matter that forms no part of the claimed design.
